ATTORNEY

UNITED STATES PATENT OFFICE.

HERMAN WILL, OF CHICAGO, ILLINOIS.

BOTTLING-MACHINE.

SPECIFICATION forming part of Letters Patent No. 331,354, dated December 1, 1885.

Application filed October 12, 1885. Serial No. 179,726. (No model.)

To all whom it may concern:

Be it known that I, HERMAN WILL, a citizen of the United States, and a resident of Chicago, county of Cook, and State of Illinois, have invented new and useful Improvements in Bottling-Machines, of which the following is a specification, reference being had to the accompanying drawings, illustrating the invention, in which—

10 Figure 1 is a front elevation of a bottling machine embodying my invention. Fig. 2 is an enlarged side elevation of one of the standard-guides, looking in the direction of arrow *x*, Fig. 1, and having in position one of the rods 15 supporting the sirup-gage; Fig. 3, an enlarged section of one of the standards, and rod and spring therein, taken on line *z*, Fig. 2.

20 The purpose of this invention is to provide a bottling machine or bench, the mechanism 20 of which can be adjusted to place, in connection with the bottling-head, pints, quarts, or other lengths of bottles, and, in general, so to improve the mechanism that the parts shall 25 operate more in harmony and be more durable, as hereinafter more fully described and shown.

It has been the custom to employ non-adjustable standards and countersink the table 30 between them to hold quart-bottles, and to 30 cover the countersunk portions with a plate to support pint-bottles. An objection to such countersunk part is the difficulty of removing broken bottles therefrom; and there 35 are also objections to the springs of such machines, in that they support by tensile force, and consequently soon become useless.

A represents the ordinary supporting table, and *B* the legs thereof, *J* being the treadle-support.

40 *C* represent hollow standards, which are supported by the table *A* by suitable flange-bearings, the lower conical parts, *E*, projecting down through the table to give longer spring-space and longer bearings to the connecting rods *F*. The standards above the table are 45 cut away from *c* to *f* at their sides, and hollowed out enough to receive the coil-springs *b*, which surround the rods *F* and extend down

into the socket parts *E*, as shown at Fig. 3. The parts *f* are cylindrical in form, and below 50 them and surrounding the rods *F* are placed sleeves *S*, and through the sleeves are tapped set-screws *d*, which turn into indentations *n n* in the rods *F*, and thus regulate the distance which the bottling-head is to be above the 55 table *A*. The lower ends of the rods *F* are connected by a bar, *C'*, through which a rod, *D*, connected with the treadle *G*, passes, and may be adjusted therein by means of a set-screw, *m*, in bar *C'*, turned into indentations in the rod *D*, the adjustments of the rods *F* and *D* being equal.

The position of the machine, as shown, is adjusted for quart-bottles. For pint-bottles the set-screws *d d* should engage depressions *n' n'* and the set-screw *m* engage indentation *a'*.

H represents the bottling-head, and *I* the frame of the sirup-gage connecting the tops of rods *F*.

To work this machine, set the bottle on the 70 table *A* between the standards *C*, connect the head *H* with the bottle in the ordinary manner, and then with the foot or treadle *G* bring down the rods *F*.

I claim and desire to secure by Letters Patent 75 of the United States—

1. In bottling-machines, the standard-guides *C C*, cut away at their sides from *c* to *f*, and recessed out to receive the springs *b*, in combination with the sleeves *S S*, carrying set-screws, and placed around the rods and in the recesses below the cylindrical parts *f*, and the springs *b*, having seats in the lower portions, *E*, of the standards, for adjusting the bottling-head, as specified. 85

2. The recessed standards *C C*, springs *b* therein, the rods *F*, provided with indentations *n n'*, and the sleeves *S* on the rods *F*, in combination with the cross-bars *C'*, adjustable rod *D*, and treadle *G*, and the bottling head *H*, as 90 specified.

HERMAN WILL.
